UNITED STATES PATENT OFFICE.

DAVID EARL HARDMAN, OF SIMMS, MONTANA.

GREASE-CUP.

1,372,427.

Specification of Letters Patent. Patented Mar. 22, 1921.

Application filed June 25, 1920. Serial No. 391,626.

To all whom it may concern:

Be it known that I, DAVID EARL HARDMAN, a citizen of the United States, and a resident of Simms, in the county of Cascade and State of Montana, have invented certain new and useful Improvements in Grease-Cups, of which the following is a specification.

My invention relates to grease cups, and a purpose of my invention is the provision of a grease cup in which there are no screw threaded portions to be removed when refilling the cup, thereby eliminating that nuisance common to the usual grease cup of remeshing the threads of one part with those of another when closing the cup subsequent to the filling operation.

It is also a purpose of my invention to provide a grease cup having a cap which is quickly and easily removed, and means associated with the cap for automatically locking the same against accidental displacement.

I will describe one form of grease cup embodying my invention and will then point out the novel features thereof in claims.

In the accompanying drawings:

Figure 1 is a view showing in side elevation one form of grease cup embodying my invention.

Fig. 2 is a vertical sectional view taken on the line 2—2 of Fig. 1.

Fig. 3 is a sectional view taken on the line 3—3 of Fig. 1.

Figs. 4 and 5 are detailed views showing in perspective the container portion and cap, respectively shown in the preceding views.

Similar reference characters refer to similar parts in each of the several views.

Referring specifically to the drawings, the grease cup essentially consists of a base B having formed integral therewith a screw threaded stem S which is adapted to be fitted within the element to be lubricated so as to support the cup as a unit thereupon. Rotatably mounted upon the base B is a container C which is adapted to receive and house the grease to be dispensed. The container C has removably fitted thereon a cap K which closes the upper end of the container, as will be understood.

As illustrated to advantage in Fig. 2, the base B and the stem S are bored axially thereof to provide a duct 15 through which

the grease from the container C is adapted to be ejected from the cup. The periphery of the base B is screw threaded, and similarly the inner wall of the container C is screw threaded to threadedly engage the base. The cap K does not threadedly engage the container C but is provided with means engageable with means upon the container for securing the cap to the container and locking the same against accidental displacement therefrom. This means, in the present instance, comprises a pair of flanges designated at F disposed at diametrically opposite points upon the periphery of the container and arranged spirally with respect to each other. As shown in Fig. 4, the widest end of each of the flanges F is provided with a lug 16, and adjacent the narrow end of each flange is a notch 17. Arranged at diametrically opposite points upon the cap K and in depending relation thereto are a pair of arms A of substantially U-shaped contour in cross section. These arms, as well as the flanges F, may be formed integral with their respective members, the arms being adapted to engage the flanges in the manner shown in Figs. 1 and 2 so that when rotated in the direction of the widest end of the flanges the arms firmly engage the same and thus secure the cap in closing position upon the upper end of the container, it being understood that the lugs 16 limit the movement of the arms into locking position. To prevent accidental disengagement of the arms from the flanges, a leaf spring R is provided, which in the present instance, is shown as being formed integral with one of the arms A and provided at its free end with an inwardly bent hook 18 which, in the applied position of the cap, is adapted to engage either of the notches 17 and to thereby lock the cap against rotation upon the container.

As shown in Figs. 1 and 2, the lower edge of the base B is beveled as indicated at 19, the purpose of which is to provide a surface against which a pair of fingers G is adapted to abut for preventing displacement of the container C from the base B. As shown in Figs. 3 and 4, the fingers G are formed at diametrically opposite points upon the lower edge of the container and are bent inwardly toward the axis of the container so as to engage the beveled edge 19 when the

container is in its uppermost position, thus preventing further rotation of the container to disengage the base.

To insure the removal of all grease from the container and base, upstanding lips L are formed within the base in the manner shown in Figs. 2 and 3, these lips serving to direct the grease to the upper end of the duct T when the container C is rotated.

10 In operation, the cap K having been removed, and the container C screwed to its uppermost position, the latter is completely filled with grease. The cap K is now applied by positioning the same so that the 15 arms A—A will be disposed between the flanges F—F so that by rotating the cap in a clockwise direction, the arms will be caused to engage the flanges in the manner previously described, and when the arms 20 have reached a securing position with respect to the flanges, the hook end 18 of the spring R automatically drops into one of the notches 17, thus locking the cap against accidental displacement. The cap having 25 been applied, the cup is now ready for dispensing of the grease, such operation being effected by a rotation of the container downwardly upon the base, thus forcing the grease into the upper end of the duct and 30 subsequently out of its lower end, as will be understood.

From the foregoing operation, it will be manifest that when filling the cup, the container C can be completely filled with grease 35 and without any waste thereof because the container, when in its uppermost position, can be completely filled without making any allowance for a plunger or other device found in the usual grease cup for effecting 40 the ejection of the grease from the cup. It will be further manifest that when the container C is screwed to its lowermost position, the upper edge of the base will engage the under side of the cap K, and under

the action of the lips L, a complete ejection 45 of the grease from the container is effected.

Although I have herein shown and described only one form of grease cup embodying my invention, it is to be understood that various changes and modifications may 50 be made herein without departing from the spirit of the invention and the spirit and scope of the appended claims.

What I claim is:

1. A grease cup comprising, a base, a container threadedly engaging the base, means for limiting the movement of the container on the base in one direction, a cap removably fitted on the container and adapted to limit the movement of the container in either direction, and means for locking the cap on the container comprising, spirally arranged flanges on the container having lugs on one end thereof and notches adjacent the other end, arms formed on the cap and engageable with the flanges, and a spring on one of the arms adapted to engage either of said notches for locking the cap against rotation.

2. A grease cup comprising, a base, a stem formed integral with the base, said stem 70 and base being bored to provide a discharge duct, a pair of upstanding lips formed in the base, a container threadedly mounted on the base, fingers formed on the container, said fingers depending from the lower edge 75 of said container and being bent inwardly to engage said base when the container is in a predetermined position, spirally arranged flanges formed on the periphery of the container adjacent its upper edge, a cap adapted to close the upper end of said container, arms carried by said cap and engageable with said flanges for securing the cap to the container, and coacting means formed on said container and cap for 80 locking the latter against accidental displacement from the container.

DAVID EARL HARDMAN.
